E. T. & E. W. COPELAND.
FIRE EXTINGUISHING APPARATUS.
APPLICATION FILED JUNE 3, 1911.

1,029,277.

Patented June 11, 1912.

UNITED STATES PATENT OFFICE.

EDWIN TURNER COPELAND AND EDWIN WARD COPELAND, OF NEW YORK, N. Y.

FIRE-EXTINGUISHING APPARATUS.

1,029,277.

Specification of Letters Patent.

Patented June 11, 1912.

Application filed June 3, 1911. Serial No. 631,121.

To all whom it may concern:

Be it known that we, EDWIN TURNER COPELAND and EDWIN WARD COPELAND, citizens of the United States, residing in New York city, New York, have invented an Improvement in Fire-Extinguishing Apparatus, of which the following is a specification.

Our invention relates to a fire extinguishing apparatus, and particularly to that class which consists in a series of automatically operated sprinkler-heads.

We are aware that heretofore there have been employed systems of fire extinguishers, in which there are sprinkler-heads so constructed as to be operated by the heat caused by a fire or in any other manner, both directly by the fire or heat therefrom coming into contact with a fusible member of the sprinkler-head, and indirectly by means causing the apparatus to operate upon a predetermined rise in temperature from any source whatsoever.

Our invention relates more particularly to the latter class of devices, and in carrying out the same, we prefer to employ a frame, a valve therein and a series of devices, one of which is separable and all of which are so related as to normally maintain the said 30 valve in position, and abnormally when the parts of the separable device are separated, to automatically release the valve so that the water or other pressure behind the same, unseats the valve and liberates itself, as will be 35 hereinafter more particularly described.

In the drawing, Figure 1 is a perspective view of the sprinkler-head forming part of our apparatus. Fig. 2 is an elevation and partial central section showing diagrammatically the electric circuits in our improved apparatus. Fig. 3 is a plan view showing one member of the separable device before the same is completed. Fig. 4 is a plan view of the same part when completed. Fig. 5 is a cross-section on line α , α , Fig. 4. Fig. 6 is a perspective view of a modified form of the device shown in Fig. 4. Fig. 7 is a cross section of this modified form of device after the same has been shaped and completed, and Fig. 8 is a cross section on larger scale showing this modified form of separable member secured to the plate member thereon.

Referring particularly to the drawing, in our improved apparatus we employ a sprinkler-head preferably consisting in a frame

or yoke 10, at one end of which there is provided a tubular exteriorly threaded portion 11, by which the yoke is connected to the leg 12 of a T-member 13 fixed in the pipe line 14 for supplying the water to the fire extinguishing system. At the upper end of the tubular member 11 and in the base of the frame 10 is a valve seat 15, upon which is normally seated a valve 16 which preferably is provided with a conical top as indicated at 17. In the top or upper portion 18 of the frame, we employ a clamp screw 19 which passes centrally through a distributor 21 such as are commonly employed in sprinkler-heads. The inner end of the clamp screw 19 is preferably conical, as indicated at 20. We also employ an arm or bar 22, on the under side of which at one end, there is a circular recess 23 adapted to receive a point of the conical top 17 of the valve 16 and on the under side at the opposite end, there is a transverse recess 24. At the upper side of this arm 22 adjacent to the portion in which the recess is provided, but offset 80 therefrom, and nearer the center of the bar, we employ a transverse recess 25.

26 designates an upright which at its lower end is preferably formed with a more or less sharpened edge to be received in the recess 25, and at its upper end with a recess 28 to receive the end of the conical portion 20 of the screw 19. Connected to or integral with this upright 26, is an arm 27 projecting upwardly and outwardly from the said arm and being provided in its upper surface adjacent to its extremity, with a recess 29.

In connection with the hereinbefore described parts we employ a heat coil member which is indicated at 30, as shown in Figs. 95 3, 4 and 5. This member preferably is made from a blank 31 of sheet metal, shaped as shown in Fig. 8, provided with the holes 32, and of the base of mica or other insulating material 33, around which a coil 34 of German silver or other wire is wound as indicated, one end of the heat coil 34 being electrically connected to the end of the cable 35, and the coil and base being surrounded by a layer of mica or other insulating material 100 52 and the opposite end 36 of the heat coil turned over this insulating casing and the coil with its base and casing placed on the blank 31 in the position shown in Fig. 3, and those portions 47 and 49 of the blank turned 105 over the central portion 48 thereof so as to form an inclosed structure. This heat coil

member is then connected to a plate 29' by a soldered joint or otherwise. As indicated in Figs. 1 and 2, when this member is in position, the edges of the openings 32 pass within the recesses 24, and the edges of the openings in the plate 29' pass within the recesses in the said arm 27. Obviously now when the parts are in the position shown in Figs. 1 and 2, and the clamp screw 19 turned 10 to place, there is more or less tension placed on the heat coil member 30, which of course maintains the parts in position. Around one side of the frame 10, we employ a collar 37 which is insulated therefrom by a layer 15 38 of insulating material, and this collar 37 is provided with a suitable terminal for electrical connection. In the pipe line 14 we also employ a collar 39 and this collar is also provided with a terminal for electrical connection.

40 indicates a thermostat, and 41 and 42 respectively the terminals thereof; 43 represents a battery or source of electrical energy. To complete the circuit, the collar 25 39 is connected to one terminal of the battery by a line 44, the other terminal of the battery being connected to one terminal 41 of the thermostat by a line 45, the other terminal 42 of the thermostat to the terminal 30 on the collar 37 by a line 46, it being understood, that the free end of the cable 35 is also secured and electrically connected by a terminal in this collar 37.

Referring to Figs. 6 and 7, it will be 35 obvious that instead of employing the metal blank 31, as shown in Figs. 3 and 4, we may employ a tube indicated at 51, within which the heat coil as hereinbefore described, may be placed and then the tube crushed or flattened as shown in Fig. 7, and then joined to the plate member of the separable device as shown in Fig. 8, by the soldered joint 50, as hereinbefore described. As will be understood, the thermostat 40 may be set to close 40 the circuit at any desired temperature and when this temperature is attained, irrespective of the cause of the rise in temperature, the electric circuit will be closed and almost instantly sufficient heat will be generated in 45 the heat coil to open the soldered joint to cause the heat coil member to separate from the plate member of the separable device, whereupon it will be understood, the arm 22, and the upright 26 with its arm 27, will 50 fall by gravity from their normal positions, thereby releasing the valve 16, permitting the water or other fluid under pressure in the pipe line 14 to unseat the valve and liberate itself. It will also be understood 55 that we have described our invention in con-

nection with a sprinkler-head for fire extinguishing apparatus, but that the same may be used for numerous other purposes without departing from the nature and spirit of the invention, and furthermore 65 that any suitable resistance may be employed in place of the German silver coil.

We claim as our invention:

1. In a fire extinguishing apparatus, the combination with a sprinkler-head, a valve 70 and separable devices for normally holding the valve closed, of members related to the latter devices and connected by a fusible joint, and an electrical heating device 75 inclosed by one of said members and in close relation to the fusible joint.

2. In a fire extinguishing apparatus, the combination with a sprinkler-head, a valve 80 and separable devices for normally holding the valve closed, of members related to the latter devices and connected by a fusible joint and one of said members comprising 85 a heat coil, an apertured plate bent over upon itself and inclosing the said heat coil so that the heat coil is in close relation to the fusible joint.

3. In a fire extinguishing apparatus, the combination with a sprinkler-head, a valve 90 and separable devices for normally holding the valve closed, of members related to the latter devices and connected by a fusible joint, one of said members comprising a heat coil, one end of the convoluted wire of which is free, an insulating covering to said heat coil against the outer surface of which the 95 loose wire is bent and a sheet metal inclosure for said heat coil and its insulating wrapping so that the free end of the heat coil wire is in close relation to the fusible joint.

4. In a fire extinguishing apparatus, the 100 combination with a sprinkler-head, a valve and separable devices for normally holding the valve closed, of members related to the latter devices and connected by a fusible joint, one of said members comprising a 105 heat coil, one end of the convoluted wire of which is free, an insulating covering to said heat coil against the outer surface of which the loose wire is bent, and a sheet metal inclosure for said heat coil and its 110 insulating wrapping so that the free end of the heat coil wire is in electrical contact with the fusible joint.

Signed by us this 26th day of May, 1911.

EDWIN TURNER COPELAND.
